UNITED STATES PATENT OFFICE.

DAVID W. CUSTER, OF SYDNEY, AUSTRALIA, ASSIGNOR TO EDWIN O. TOWNSEND, OF MANSFIELD, OHIO.

METHOD OF AND APPARATUS FOR STONEWORKING.

1,313,269.

Specification of Letters Patent.

Patented Aug. 19, 1919.

Application filed January 23, 1918. Serial No. 213,374.

To all whom it may concern:

Be it known that I, DAVID W. CUSTER, a citizen of the United States, residing at Sydney, Australia, have invented certain new and useful Improvements in Methods of and Apparatus for Stoneworking, of which the following is a specification.

This invention relates to the manufacture of relatively large monolithic stone receptacles such as bath tubs and the like, and more particularly has special reference to making the same from blocks of solid stone.

Heretofore, in making bath tubs of marble great waste of this valuable stone has been incident to the removal or hollowing out of the central body portion of the block, since owing to the previous methods this large body of stone has become broken or mutilated to such an extent that it is unfit for further use. Accordingly, the present invention contemplates a novel method whereby the interior or core portion of the block may be removed in its entirety and saved for other uses, thereby resulting in greatly increased economy in the working of the stone, and also materially diminishing the cost of the finished product.

With the above and other objects in view which will more readily appear as the nature of the invention is better understood, the same consists in the novel construction, combination, and arrangement of parts herein-after more fully described, illustrated, and claimed.

The essential features of the invention are necessarily susceptible of modification to a reasonable extent, without departing from the scope of the appended claims, but for the purposes of illustration, the drawings show a preferred method of carrying the invention into effect, both as to process and means.

In the drawings—

Figure 1 is a perspective view of a solid block of marble illustrating the first step of the present method, wherein substantially vertical holes of suitable diameter are made at a proper distance from each corner of the block.

Fig. 2 is a cross-sectional view on the line 2—2 of Fig. 1.

Fig. 3 is a perspective view similar to Fig. 1, illustrating the second step of the method, wherein the holes formed by the first step

shown in Fig. 1 are directly connected by a looped channel, thus isolating the central portion of the block and forming the core which only remains connected with the body at the bottom. This figure also indicates by dotted lines an incidental step in the method which consists in making the original holes slightly larger for the purpose of receiving a portion of the cutting apparatus as will hereinafter more fully appear.

Fig. 4 is a horizontal cross-section taken on the line 4—4 of Fig. 3.

Fig. 5 is a perspective view illustrating the next step of the method, wherein the core severing apparatus is placed in position on the block to cut the core at its bottom from the block body.

Fig. 6 is a section illustrating the next step of the method wherein the core is partially severed from the body block.

Fig. 7 is a view similar to Fig. 6 showing the next step of the method wherein the apparatus is reversed, to complete the severing of the core from the body block.

Fig. 8 illustrates the final step in the method wherein the completely severed core is removed from the body block.

Fig. 9 is a perspective view of the finished article.

Fig. 10 is a perspective view of one of the roller carrying bars of the severing apparatus.

Similar references designate corresponding parts throughout the several figures of the drawings.

In carrying the present method into effect it is proposed to operate upon a block of marble 1 of suitable shape and dimensions, according to the style and character of the tub to be made, and then provide this block in each corner portion thereof with a substantially vertically disposed guide hole 2. These holes may be formed by any suitable or well known drilling device and extend from the upper surface of the block to the required depth, for instance three inches from the bottom.

According to the next step of the invention, it is proposed to connect all of these guide holes by a plurality of communicating channels 3, which may be formed by a suitable channeling machine to make a continuous freeway in the body of the block and leave a central core portion C which is

completely isolated from the body block on all sides to the original depth of the holes 2, but remains united therewith at the bottom of the block. This step of the invention 5 is clearly shown in Figs. 3 and 4 of the drawings. After the continuous channel 3 is formed in the body block, it is desirable to slightly enlarge the original corner holes 2, as indicated by dotted lines 2', whereby 10 the apparatus for separating the bottom of the core from the body block may be readily inserted and operated.

Fig. 5 illustrates the next step in the method wherein the core severing apparatus 15 is clamped to one end of the block so that a portion thereof extends down into the pair of holes 2 which are located at one end of the block, whereby the severing or cutting wire W thereof may be looped around the 20 end of the core C opposite the apparatus, as indicated by the dotted lines in Fig. 5. The location and operation of the core severing apparatus in this step of the method is shown in Fig. 6 of the drawings, wherein 25 the cutting wire W appears as having cut a portion of the core C from the body block, the dotted lines c indicating the extent to which the core is severed by the apparatus in the position shown in Fig. 6. It will, of course, be understood that the cutting action 30 of the wire W is facilitated by placing in the channel 3 a suitable mixture of water and sand, or water and steel shot.

After the apparatus has severed about 35 one-half of the core from the body block, it is reversed, as shown in Fig. 7, whereby the cutting wire W starts a fresh cut at the opposite end of the core which will meet with the previously formed cut made with the 40 apparatus, as shown in Fig. 6. This reversal of the apparatus greatly facilitates the cutting action of the wire, since as the wire gets deeper in its slot, its cutting pressure is materially reduced. After the core C is 45 thus completely severed by this step of the method it is then suitably removed, as indicated in Fig. 8, and the result is the hollow shell body or tub shown in Fig. 9.

Referring now to one type of apparatus 50 for severing the bottom of the core from the body block, it will be observed from Fig. 5 that the same may comprise a pair of roller-carrying guide-bars 4, adapted to fit into the enlarged vertical openings 2', and having 55 at their lower ends the wire-receiving and guiding rollers 5, preferably of a waterproof and ball-bearing type to eliminate as much friction as possible. These guide-bars 4 are rigidly held in place within the openings 2' by means of a clamping frame designated generally as F, and which preferably 60 comprises an upper shaft clamping cross bar 6, and a lower block engaging bar 7 which are joined by means of vertical connecting rods 8, having at each end thereof

the removable nuts 9, whereby the frame may be readily and quickly clamped to and removed from the end of the block.

It will of course be understood that any suitable framing may be used for holding together the various parts of the apparatus in operative relation, and any suitable driving means and driving connections may be employed. However, as shown in the drawings, the rear side edges of the guide bars 70 4 may be provided with a groove 4' as shown in Fig. 10 of the drawings, whereby the cutting wire W after passing around the core C will have a free exit out of the upper or outlet ends of the holes 2', from whence it may pass over suitable guide pulleys 10, and thence over other pulleys (not shown), whereby it will have a considerable run before reentering the channel 75 in the block to again perform its cutting function. The purpose of giving the wire a long run is to permit it to cool after leaving the block so that upon again entering the same for the cutting operation its hardness and cutting efficiency will not be impaired. 80 90

From the foregoing it will be apparent that the novel and distinctive feature of the present invention is the making of hollow receptacles from solid blocks of stone, by removing the core of the block as a whole in 95 an unbroken condition, and to this end there is employed a novel cutting saw in the form of a flexible wire, which, by the use of the type of apparatus shown, can sever the core from the body block with ease and facility. 100

I claim:

1. A method of making monolithic stone tubs or the like which consists in first forming guiding holes to a partial depth in the corner portions of the stone block, then connecting said holes by forming a channel within the body and through the holes, and subsequently severing the core, left by forming the channel, by cutting it from the body in substantially the same plane as the bottoms of the said guide holes. 105 110

2. A method of making monolithic stone tubs or the like from solid stone blocks which consists in first forming a series of holes in the block, and then connecting each of said holes by a channel to form a central core portion which is isolated from the body block at the sides and ends but still connected at the bottom, then enlarging said holes to receive a portion of a core bottom severing apparatus, then severing the bottom of the core from the block, and subsequently removing the core from the body-shell. 115 120

3. A method of making monolithic stone tubs or the like from solid stone blocks which 125 consists in first making a series of guide holes in each corner portion of the block, and then connecting said holes by a plurality of communicating channels to form a central core portion which is isolated from 130

the sides and ends of the body block but connected at the bottom, then severing the bottom of the core from the body block, and subsequently removing the core block as a unit from the body-shell thus formed.

4. A method of making monolithic stone tubs or the like from solid stone blocks which consists in first making a series of guide holes in the block, then connecting 10 said holes by a channel to form a central core portion which is disconnected from the sides and ends of the body block, but still connected at the bottom, then severing the bottom of the core from the body block, and 15 subsequently removing the unbroken core from the body-shell.

5. A method of making monolithic stone tubs or the like from solid stone blocks which consists of first making a series of holes in 20 the block, and then connecting said holes by a channel to form a central core portion which is disconnected from the sides and end of the body block but still connected at the bottom, and then partially severing the 25 bottom of the core from the body block by looping a moving continuous flexible cutter

around the end of the core opposite its entrance into the channel, then reversing the position of said cutter whereby the same will complete the severing of the core from the 30 body block in the opposite direction and subsequently removing the unbroken core from the body shell.

6. A process for making hollow receptacles from solid stone blocks which consists 35 in first making a continuous channel to a partial depth of the block, then cutting the core surrounded by the channel from the body of the block by applying a flexible cutter to one end of said core at the bottom of 40 the channel to make a cut at right angles to the latter toward the center of the block, then applying said flexible cutter to the opposite end of the core to cut in the reverse 45 direction, and subsequently removing the severed core as a unit.

In testimony whereof I hereunto affix my signature in the presence of two witnesses.

DAVID W. CUSTER.
